UNITED STATES PATENT OFFICE.

HARRY B. CURTIS, OF HUNTINGTON, CONNECTICUT, ASSIGNOR TO BRIDGEPORT HARDWARE MANUFACTURING CORPORATION, OF BRIDGEPORT, CONNECTICUT, A CORPORATION OF CONNECTICUT.

DISPLAY STAND.

Application filed May 28, 1928. Serial No. 281,189.

This invention relates to a display stand, particularly a stand for displaying tools, such as screw drivers and the like, and has for an object to provide an improved stand 5 of this character which will be neat and attractive in appearance, and will hold the articles to be displayed in such a manner that each individual article may be easily inspected or examined and also to hold them 10 in such a manner as to attract attention.

It is a further object of the invention to provide a device of this character which is very simple in construction and may be manufactured and assembled at low cost.

15 It is another object of the invention to provide a display stand of this type which may be folded into a small space so that it may be packed in the box with the articles to be displayed.

20 With the foregoing and other objects in view, the invention consists in certain novel features of construction and arrangement of parts as will be more fully described in connection with the accompanying drawing. In 25 this drawing,

Fig. 1 is a perspective view of the display stand in use showing the manner of supporting tools therein for display.

Fig. 2 is a top plan view of the stand in 30 folded condition, and

Fig. 3 is a detail section substantially on line 3—3 of Fig. 2 on an enlarged scale.

This display stand is very simple in construction involving a minimum number of 35 parts. As illustrated it comprises a pair of substantially inverted U-shaped frame members 10 of flat strip metal and with the free ends of the upright side members bent inwardly to form supporting feet 11. Extending 40 transversely between the upright sides 10 is a cross bar 12 of similar strip metal bent laterally at its opposite ends to form ears 13 by which this bar may be secured to the side members 10 of the frame. This 45 cross bar may be secured by any suitable securing means, such as spot welding, as indicated at 14, or other suitable means, such as rivets if preferred, and the bar 12 is located at any suitable height or distance

from the cross member 13 of the frame depending on appearance and the length of the articles to be displayed.

The stand shown comprises two frame members 10 and two cross bars 12, the cross members 15 being pivoted together at 16 50 while the cross bars 12 are pivoted together at 17 at substantially their mid lengths. If preferred the metal of the bars may be pressed laterally, as shown at 18, to provide a spacing rib so that when folded together 60 the bars will not interfere with each other. The pivots are formed by suitable rivets 19.

The horizontal bars 12 and 15 are provided with a plurality of sets of aligned 65 openings 20 for insertion of the blades and shanks of the tools 21. These tools in the present case are shown as screw drivers. Of course, the openings 20 will be of a size to properly receive and support the tools in the manner indicated, and preferably with 70 the shoulder between the shank and the handle resting on top of the bar 15 thereof.

In transportation the stand is folded to the condition shown in Fig. 2, and may be packed in the box with the tools. After unpacking, the stand is set with the two sections of the frame at substantially right angles, as shown in Fig. 1, and the tools inserted as indicated. This is a very simple and effective construction which so supports 80 the tools that each is individually accessible for inspection and may be withdrawn without interfering with the other articles. At the same time they are supported in such a manner as to attract attention when the device is placed on a counter.

Having thus set forth the nature of my invention, what I claim is:

1. In a display stand, a pair of frames each comprising a strip or bar of flat metal 90 bent to inverted substantially U-shape with their top connecting portions pivoted together, a cross bar of similar flat material connected to the upright side portions of the frame members and extending between 95 them below the top portion thereof, said cross bars and said top portions being provided with aligned openings to receive and

support tools to be displayed in an upright position.

2. In a display stand, a pair of upright frames extending transversely of each other and secured together, each frame comprising an inverted substantially U-shaped member and a cross bar extending between and con-

nected to the upright side portions thereof below the top connecting portion, and said cross bars and top connecting portions having aligned means for supporting the tools to be displayed in an upright position. 10

In testimony whereof I affix my signature.

HARRY B. CURTIS.
